SEIICHIRO SENGA AND SEIJI NISHIKAWA, OF TOKYO-FU, JAPAN, ASSIGNEES TO THE
KANEYAFUCHI BOSEKI KOUUSHIKI KWAISHA, OF TOKYO-FU, JAPAN.

FILAMENT SUPPLIER.

Application filed August 1, 1923, Serial No. 655,137. Renewed July 18, 1925.

To all whom it may concern:

Be it known that we, SEIICHIRO SENGA and SEIJI NISHIKAWA, subjects of the Emperor of Japan, residents of Tokyo-Fu, Japan, have invented certain new and useful invention of Improvements in Filament Suppliers, of which the following is a specification.

Our invention relates to improvements in filament suppliers for use in silk reeling machines and has for its object to supply filaments to silk reeling machines easily and reliably by means of simple arrangements. Another object of the invention is to minimize the knots or frizzles of the silk strand 15 to be formed at the joining points of filaments so that the nature of raw silk is improved.

The invention comprises a metal or porcelain or any other smooth wire projecting its 20 arm horizontally sideward at the lower part of the vertical revolving spindle provided with a fine hole at its centre to make filaments or a silk strand pass through it in silk reeling machines of any known type.

At the inner end of said projecting arm a spiral annulation is formed a little beneath the lower end of the spindle and continuous to the other end of said spiral annulation a spiral or inclined guide is formed around 25 the lower part of the spindle leaving a little space between the latter. The spiral annulation and the spiral or inclined guide is made successively of the same wire to form the main part of the supplier and at 30 the upper end of the guide the wire is fixed to the side of the spindle or a revolving sleeve at a point a little above the lower end of the spindle. A cocoon, with its filament unloosed and held above, is dropped beside 35 the supplier, and according to the revolution of the latter the filament is caught at the arm of the supplier and sliding along it is taken toward the centre. After some revolutions of the supplier the taken in part 40 of the filament is directed substantially parallel to the spindle by means of the spiral annulation and spiral or inclined guide and then is adjoined to the other filaments which are in the course of reeling and the 45 end of the supplied filament is cut while reeled up together with the other filaments through the spindle to form a silk strand.

It is already known in filament suppliers to take in the filament of a dropped cocoon 50 by means of horizontally projecting arms,

but in those filament suppliers of the type the supplied filament is adjoined to other filaments immediately as it is taken in so that the pressure of the supplied filament on the other filaments or silk strand being 60 weak does not attain enough pressure to stick fast on the running strand unless after the supplied filament is wound several times on the former which gives rise to a notable knot on the strand at the joining point of 65 the filament. According to the present invention the filament when taken into the centre of the supplier does not come in contact with the running filaments at once, but the taken in part of it being previously 70 directed parallel to the spindle or running strand before it is brought in contact with the other filaments by means of the spiral annulation and the spiral or inclined guide 75 successively formed at the inner end of the projecting arm, and afterward is adjoined to the other filaments, the pressure of the supplied filament on the running filaments is remarkably increased and thereby immediately sticks fast and is reeled up together 80 with the running filaments without awaiting for being wound several times. Thus the formation of jointing knots on the strand is avoided. Furthermore, in those filament 85 suppliers of the type wherein the other end of the supplied filament is cut by the tension of the running strand, the fixed end of the filament is generally stretched sideways and at the moment of being cut the end of the filament rebounds oppositely sideways 90 and being apt to project out of the strand forms knots or frizzles at the jointing points of filaments. According to the present invention the taken in part of the filament 95 being previously brought parallel to the strand by means of the spiral annulation and spiral or inclined guide as stated, when said part of the filament is cut by the tension of the strand it rebounds downward parallel to the strand and as it is rubbed on the running filaments by the revolution of the spiral annulation the frizzled end of the supplied filament becomes adhered to the strand and the formation of frizzles is also entirely avoided.

The annexed drawing shows the filament suppliers embodying the present invention. Fig. 1 is an elevation, partly in section of the filament supplier. Fig. 2 is a plan view 100 of the wire forming the essential part of the 105 110

invention. Figs. 3 and 4 are enlarged views of the supplier showing the action of supplying a filament. Fig. 5 is an elevation partly in section of a modified supplier. Referring to Fig. 1, a spindle (1) of the silk reeling machine of any known type is conically tapered at its lower end and provided with a fine hole at its centre to make a silk strand pass through. The spindle is vertically mounted on an arm (2) of the frame work and is made to revolve by a grooved pulley (3) or any other suitable driving mechanism. A filament supplier (4) made of metal wire, porcelain or any other smooth wire is arranged at the lower part of the spindle. It comprises an arm (4₁) horizontally projecting sideways with a suitable curvature. At the inner end of said arm (4₁) a spiral annulation (4₂) is formed a little beneath the lower end of the spindle (1). Successive to the other end of the annulation (4₂) a spiral guide (4₃) is formed around the lower end of the spindle (1) with a little space between the latter. Said arm, annulation and guide are successively made of the same wire (4) and the upper end of the guide (4₃) is bent and fixed to the side of the spindle (1) at a point a little off the lower end of the latter.

In a modification shown in Fig. 5 an inclined guide (4'₃) is formed with a little space around the spindle (1), in place of the spiral guide (4₃) in Fig. 1. The spindle (1) in place of being made to revolve as shown in Fig. 1, may be fixed on the frame work as shown in Fig. 5. A sleeve (5) provided with a grooved pulley (3), is rotatably arranged around the spindle (1), and the upper end (4₄) of the inclined guide (4'₃) is fixed at the side of said sleeve.

When it is desired to supply a filament to the silk reeling machine a cocoon with its filament unloosed and held above is dropped beside the supplier as shown in dotted lines (a) in Fig. 1. According to the revolution of the arm (4₁) the filament is caught and sliding on it is taken toward the centre of the filament supplier as shown at (b) in Fig. 1. When the supplier further revolves the upper part of taken in filament ascends along the spiral guide (4₃) (or the inclined guide (4'₃) in case of Fig. 5) while its lower part being sustained at the spiral annulation (4₂) the taken in part of the filament becomes directed substantially parallel to the axis of the spindle without making contact with other filaments (d) which are in the course of reeling as shown in dotted lines (c) in Fig. 3. When the upper end of

the taken in filament reaches to the upper end (4₄) of the guide (4₃) it can slide no more along said guide and the supplied filament revolves together with the spindle (1) and the filament suppliers, so that the filament is twined on the other filaments (d) at the lower end of the spindle (1) as shown at (e) in Fig. 3. The filament (e) being previously stretched parallel to the spindle by the action of the spiral annulation and guide, presses more intensely on the other filaments (d) in comparison with those filament suppliers hitherto in use, and instantly produces sufficient pressure to stick fast on the running filaments without twining on the latter several times, thus the formation of notable knots at the jointing points of filaments is avoided. After the supplied filament has stuck fast on the other filaments it is reeled up together through the hole of the spindle to form a strand, and the upper part of the supplied filament is cut by the tension of the running strand. As the supplied filament is previously directed parallel to the spindle, the end of the filament rebounds downward as shown in dotted lines (f) in Fig. 4. The supplied filament is reeled up together with other filaments in the course of reeling as stated, the hanging end (f) of the supplied filament is rubbed on the conical surface of the other filaments (d) by the revolution of the spiral annulation (4₂) while the former are reeled up as shown at (g) in Fig. 4, and the frizzled end of the supplied filament becomes closely adhered to the strand. Thus the jointing point of the supplied filament is rendered smooth and inconspicuous and therefore the nature of raw silk to be manufactured is remarkably improved.

We claim:—

In a silk reeling machine, a vertical spindle provided with an axial bore to permit filaments to pass through the same, and a smooth wire including a substantially horizontal arm projecting outwardly from the axis of the spindle, and having its inner end of spiral formation, the spiral portion extending both above and below the lower end of the spindle and surrounding the axis of the latter, the upper part of the spiral portion being spaced from the lower end of the spindle, said spindle including a sleeve to which the upper part of the spiral portion of the wire is connected, and means for rotating said sleeve.

In testimony whereof we have affixed our signatures.

SEIICHIRO SENGA.
SEIJI NISHIKAWA.
